UNITED STATES PATENT OFFICE

158,897

COMBINED HANDBAG, LUNCH BOX, AND
VACUUM BOTTLE

Wentzle Ruml, Jr., East Orange, N. J.

Application January 19, 1949, Serial No. 340

Term of patent 7 years

(Cl. D87—3)

To all whom it may concern:

Be it known that I, Wentzle Ruml, Jr., a citizen of the United States, residing at East Orange, in the county of Essex and State of New Jersey, have invented a new, original, and ornamental Design for Combined Handbag, Lunch Box, and Vacuum Bottle, of which the following is a specification, reference being had to the accompanying drawings, forming a part thereof.

In the drawings:

Fig. 1 is a perspective view of a combined handbag, lunch box, and vacuum bottle with the handbag compartment in an open position;

Fig. 2 is an enlarged perspective view thereof with the handbag compartment closed;

Fig. 3 is a perspective view of the opposite side from that shown in Figs. 1 and 2 with the lunch box compartment in an open position;

Fig. 4 is an enlarged perspective view of the combined handbag, lunch box, and vacuum bottle

illustrating both compartments in open position; and

Fig. 5 is an enlarged perspective view of the removable shelf element of the lunch box compartment.

I claim:

The ornamental design for a combined handbag, lunch box, and vacuum bottle, as shown.

WENTZLE RUML, JR.
